PLUNGER AND CYLINDER FOR PUMP

Anthony E. Giraudeau, Toledo, Ohio, assignor to The National Supply Company, Pittsburgh, Pa., a corporation of Pennsylvania

Application March 9, 1953, Serial No. 341,279

1 Claim. (Cl. 103—153)

The invention has to do with water flood pumps and more particularly with the plunger, cylinder, and stuffing box arrangement of water flood pumps.

It is the custom in the oil fields when a field is depleted to an extent such that production is no longer profitable, to pump water down some wells in order to force the remaining oil in the formation toward another well so that the oil may be recovered therefrom in the normal fashion. This systematic driving of oil to a producing well is called water flooding. In order for this to be effective the pumps must maintain the water pressure down the wells at about 2000 p. s. i. To release this pressure means losing the drive on the oil with a consequent loss of production. It is therefore desirable to maintain the pumps in operation at all times and to have shut-down time at a minimum.

It is an object of this invention to employ a pump which is simple to assemble and is susceptible of rapid and easy replacement of wear parts.

A particular object of the invention is to make the cylinder head and the stuffing box an integral unit, so as to permit quick removal and replacement of the stuffing box.

Another object of the invention is to make the plunger removable from the crosshead, so as to permit removal and replacement of the stuffing box and the plunger as a unit. In practice it has been found that the stuffing box packing is the first part to need replacement, and it needs replacement often. Heretofore this required removal of the gland nut, the removal of the old packing, the tedious repacking, ring by ring, of the new packing, and, finally, the replacement of the gland nut. Since the time element is so important, often a hurried job of placing the packing over the plunger is done wrong, and the job must be done again. The present invention greatly reduces this detrimental non-operating time by requiring only the steps of unfastening the plunger and cylinder head and removing a gland nut from the stuffing box, then removal and replacement of the entire unit, a job easily and quickly handled by only one man. The replacement of the stuffing box packing and the positioning of the plunger therein can then be done at leisure at the bench in the spare unit while the pump is running.

Another object of the invention is to provide a pump arrangement such that a change in plunger size can be rapidly made. The plunger size can be changed in the same manner that a stuffing box is replaced, merely inserting a unit with the desired new plunger and stuffing box sizes.

A still further object of this invention is to provide a cylinder, plunger arrangement which has a minimum end clearance for greater efficiency in cylinder filling.

Other objects will become apparent from the description of a preferred embodiment hereinafter described and claimed, reference being made to the accompanying drawings forming a part of this disclosure, wherein like numerals refer to like parts, and in which drawings:

Fig. 1 is a side elevation of the water flood pump, showing the cylinder, plunger, stuffing box arrangement.

2

Fig. 2 is an end view of the pump showing the removable cylinder heads.

Fig. 3 is an enlarged fragmentary view of Fig. 1 showing the plunger and stuffing box arrangement.

5 Fig. 4 is a perspective view of the cylinder head, stuffing box unit.

The water flood pump designated generally at 1 has a casing 2 with a crankshaft 3 rotatably mounted in one end thereof. The crankshaft 3 has a crankpin 4 on which 10 is mounted connecting rod 5. The pump may be of any desired number of cylinders, each being identical in structure and function, so that the description of one cylinder arrangement will suffice for all. The connecting rod 5 is in turn connected by means of wrist pin 6 to the crosshead 7. The crosshead 7 is mounted in guideways 8, which are an integral part of the casing 2, for 15 sliding movement therein. The crosshead has a cross-head rod 9 formed as an integral part thereof and extending parallel to the direction of reciprocation of the 20 crosshead. The rod 9 extends through bore 10 in the casing 2. Plate 11 is secured to the casing 2 by means of screws 12 and carries seal 13 through which the rod 9 passes, sealing the crosshead guides 8 against foreign 25 material from outside the casing 2, and forming a sealed lubricant chamber 14 within the casing for the moving parts.

The outermost end of the rod 9 is threaded at 15 for the mounting of the removable plunger 16. Plunger 16 30 may be metal, ceramic, or ceramic coated metal and has an internally threaded end 17 to mate with the threaded end 15 of rod 9. The outer end surface of the plunger can be hexagonal to facilitate the mounting of the plunger on the rod with a wrench.

Casing 2, at the opposite end from the crankshaft 3, 35 has the fluid end 20 of the pump mounted thereon. The fluid end 20 has inlet valve 21 and discharge valve 22 mounted therein. A bore 23 concentric with the axis of the plunger 16 forms part of the chamber 24 in the fluid end. A hollow sleeve 25 closed at one end 26 is 40 mounted in bore 23. The sleeve 25 is bored transversely at 27 and 27a to permit passage of the working fluid through the chamber 24. At the closed end of the sleeve a flange 28 integral therewith has studs 29 passing therethrough to secure the sleeve in the bore 23 by means of nuts 29a. Sealing rings 30 and 31 are used between the sleeve and the fluid end to seal the chamber 24 from the atmosphere. The bore 32 of the sleeve 25 is of a diameter slightly greater than that of plunger 16. And the end 26 of the sleeve is so placed that a minimum end 45 clearance is had between the plunger 16 and the end wall 26 when the plunger is at the extreme limit of the pumping stroke. Ring 33 is a guide ring engaging in annular groove 34 of the casing 2 and annular groove 35 of the fluid end 20 to facilitate alignment of the parts 50 when the fluid end is mounted on the casing by means of studs 36.

The sleeve 25 is of sufficient length to extend into the casing 2 and surround the plunger 16 over a considerable portion of its length so as to form the stuffing box 37 therewith. The sleeve 25 has a counterbore 38 at its 60 open end, of a diameter greater than that of bore 32 thereby forming a shoulder 39 therebetween. Mounted in the counterbore 38 is a junk ring 40 which is of a sufficient width so the plunger 16 in its most retracted position during operation will not withdraw from the ring. 65 Packing rings 41 are mounted in the counterbore adjacent ring 40 and a follower gland 42 is mounted in the counterbore adjacent the packing rings. The outside surface of the sleeve 25 is threaded at 43 and a gland nut 44 is mounted thereon. The nut 44 has a shoulder 45 70 which engages the gland 42. Thus a tightening of the nut 44 will compress the packing rings between shoulder

45 of the nut and shoulder 39 of the sleeve, forcing them radially inwardly into sealing engagement with the plunger 16.

The operation of the device is as follows. During normal operation of the pump it may become necessary to replace the packing rings 41 of the stuffing box. A spare unit including the sleeve member 25, the packing elements, and the plunger mounted therein is brought to the pump from the work bench. The pump is then shut down. Nuts 29a are removed so as to permit removal of sleeve 25. The plunger 16 is unscrewed from rod 9. Gland nut 44 is removed and can be hung on rod 9, and the remaining assembly is pulled out through the fluid end. The spare unit, including plunger, packing, and sealing rings 30 and 31, is placed in the bore 23 and the connections reassembled. Thus in a very short time a complete change can be made by one man and the pump again started. The removed unit can then be taken to the work bench, the plunger removed and inspected, the packing rings replaced, the plunger put back in the packing and the unit can be used as the next replacement unit. While the pump is running, time can be taken to do an adequate replacement and repair job, and no time-cutting short cuts are needed, which may result in inadequate parts replacement.

If it is desired to change the plunger size, the same procedure would be followed. A unit made up of a plunger and stuffing-box assembly of the desired size would be used as the replacement unit.

Having fully described my invention, what I claim as new and desire to secure by United States Letters Patent is:

A pump comprising a cylinder block having a bore therethrough, inlet and outlet ports in said block opening laterally into said bore and having inlet and outlet valves mounted respectively therein, drive means including a reciprocating member, a plunger removably attached to said reciprocating member, a stuffing box cartridge mounted in said bore, said cartridge comprising a cylindrical sleeve surrounding said plunger and having ports 40 in communication with the inlet and outlet ports in said

cylinder block, a flange integral with one end of said sleeve remote from said reciprocating member forming a closure head for both said sleeve and said cylinder bore and engaging said cylinder block for securement of said sleeve to said block, said sleeve extending a substantial distance beyond said cylinder block toward said reciprocating member and terminating in an open, externally screw-threaded end, a counterbore in said open end of said sleeve, an internal shoulder formed by the end of said counterbore remote from said reciprocating member, an adjustable packing mounted in said counterbore, abutting said shoulder, and engaging said plunger in sealing relationship therewith, a follower gland slidable in said sleeve and adjustably engaging said packing on the side of said packing toward said reciprocating member, and an internally screw-threaded gland nut screw-threadedly received on said externally screw-threaded end of said sleeve, said nut having an inwardly directed shoulder on the side of said nut adjacent said reciprocating member, said shoulder adjustably engaging said follower gland endwise against the end of said follower gland toward said reciprocating member to slide said follower gland in said sleeve, thereby to adjust said packing, and said plunger, sleeve, flange, packing and follower gland being removable from and replaceable in said cylinder bore as a unit.
